CLAIM

The ornamental design for a front panel for an electric fence insulator, as shown and described.

DESCRIPTION

FIG. 1 is a perspective view of a front panel for an electric fence insulator showing our new design, the broken line drawing is for illustrative purposes only and forms no part of the claimed design;

FIG. 2 is a front elevational view thereof;

FIG. 3 is a top plan view thereof;

FIG. 4 is a bottom plan view thereof; and,

FIG. 5 is a right side elevational view thereof, the left side being a mirror image.
